UNITED STATES PATENT OFFICE.

FREDERICK H. KNAPP, OF WESTMINSTER, MARYLAND.

SHADE-CARRIER.

1,203,629.

Specification of Letters Patent. Patented Nov. 7, 1916.

Application filed August 3, 1914. Serial No. 854,853.

To all whom it may concern:

Be it known that I, FREDERICK H. KNAPP, a citizen of the United States of America, residing at Westminster, Carroll county, 5 State of Maryland, have invented certain new and useful Improvements in Shade-Carriers, of which the following is a specification.

This invention relates to a window shade 10 fixture or carrier of the general type in which both the roll and stick are adjustable up and down the length of the window so that the shade may be arranged to screen any portion of the window desired giving a 15 corresponding variation as to the amount and distribution of light admitted.

In fixtures of this general type described in previous patents taken out by me, the roller and in some instances, the stick are 20 mounted on carriages or followers which move up and down on suitable ways or guides on the window frame or casing. These guides are sometimes in the form of grooves in which the slides travel, but more 25 frequently, they are in the form of rods inclosed by the followers. To give the requisite traverse, the rods must extend the entire length of the window being supported at the top and bottom only. Under these circumstances, particularly with long windows, in 30 order to give the stiffness required to resist the tendency to flap which is incident to the exposure of the shade to even normal summer breezes, the rods must be made of com- 35 paratively large diameter and weight so that they are cumbersome in appearance, expensive to supply and not convenient to handle and ship. It is also an incident to the use of such fixtures that they cannot always be 40 placed in the same position relatively to each other and to the casing. In some instances, they must be placed on the inside or inwardly disposed faces of the casing, while at other times, it is more convenient or de- 45 sirable to place them on the front or outer face of the casing. The prior devices are not ordinarily interchangeable for this purpose in the sense that they can be used in both positions without any variation of the 50 structure, and those which are described as interchangeable are either so elaborate that they cannot be used on account of the expense, or are otherwise objectionable. Others, while described as interchangeable, 55 are not so as to all their parts, certain variations being necessary to the adaptation of

the structure intended to be mounted in one position, for use in another position.

The device of the present invention is de- 60 signed to overcome all the difficulties herein recited. To this end, the guide consists of a flexible metal strip which is thin and light and may be coiled for shipment, a convenient feature in the mail order trade, and to overcome the excessive flexibility due to the 65 use of a thin guide rod, supports are provided at short intervals, the followers which are designed to inclose the guide rods, having a small slot to pass the supports in the 70 traverse of the follower.

The difficulty ordinarily encountered in 75 rendering the device interchangeable so that it can be mounted either on the front or inner face of the window frame, has been most satisfactorily dealt with in the present instance. The ears or plates in which the roll pivots are carried, are shown in a previous patent issued to me as pivotally mounted on the slide. In the present instance, in order to render the fixture interchangeable, I use 80 a universal, instead of a hinge joint, both in connecting the roll-carrying ears to the upper slides, followers or carriers and in connecting the stick to the lower followers. Thus mounted, the parts may be rotated in 85 a horizontal plane relatively to each other as well as in a vertical plane as in my previous constructions and are thus applied to the front or inner face of the casing without change. The upper supporting bracket carrying the pulleys and, if necessary, the upper ends of the guides, may be used without 90 change on either face of the casing.

An important advantage of the present 95 structure is that the brackets, guide rods, followers and ears, *i. e.*, practically the whole structure, is so designed that the parts may be easily and conveniently stamped out of sheet metal and bent to shape, saving a 100 very large portion of the cost which would otherwise be incident to the manufacture of such a construction.

A window shade carrier embodying the 105 various features of my invention in its preferred form is illustrated in the accompany- drawing, the same being applied both to the front and inner face of the window casing.

Figure 1 is a front elevation of a window 110 showing a shade and the fixture applied to the front face of the casing; Fig. 2 is a horizontal section on the line 2, 2 of Fig. 1; Fig.

3 is a side elevation taken from the left of the window as seen in Fig. 1; Fig. 4 is an elevation looking from the right; Fig. 5 is a section corresponding to Fig. 2 showing the fixture applied to the inner faces of the casing; Figs. 6 and 7 are detail views of the universal joint connecting the stick to the stick carrier, showing the same in the two positions prescribed; these views may be considered as taken on the line 6, 7 in Fig. 9; Fig. 8 is a section on the line 8, 8 of Fig. 9; Fig. 9 is a fragmentary elevation of the lower portion of the shade showing the stick carriers and connections; Fig. 10 is a detail view of one roll carrier and ear; and Figs. 11, 12 and 13 show the pulley bracket in top, side and bottom views, respectively.

Referring to the drawings by numerals, each of which is used to indicate the same or similar parts in the different figures, the device consists of a shade roll 1, mounted in carriages 2 to move up and down the length of the window, the carriages traveling on the guides 3 and the stick being connected to stick carriers 4 which also move up and down the guides 3.

In the form of the invention shown, the guides 3 are in the form of flat straps or bands supported at their ends and intermediate by means of studs 5 illustrated as consisting of a central pin 6 secured to the guide rod and seated in the casing, the pin being passed through a cone 7 having its base resting on the face of the casing 8.

The carriages 2 consist each of a slide or follower 9 to which an ear 14 suitably slotted to receive the pivot pin of the roll is connected by means of a universal joint 11. The joint preferably consists of a tab or tongue 10, see Fig. 10, cut out of and turned up from the metal out of which the slide is made, and pierced in a horizontal direction at 13, the ear 14 being a flat piece of sheet metal slotted at 15 or 15', see Figs. 3 and 4, respectively, to admit the pivots of the roll. Both the flat and round terminals 16 and 16' are referred to as pivots. The ears on the two sides are substantially similar except as to the slots 15, 15'. For greater accuracy, the right-hand ear will be indicated by reference character 17'. The ear 14 has an extension or projection at one lower corner, the same being formed into an eye or hook 12, see Fig. 2, which engages the eye 13 of the tab 10 on the slide. To insert the roll pivots into the slots 15 and 15' in the ears, the latter members are merely swung outward and the pivot ends 16 and 16' passed into the slots, the ears being then swung back into parallel relation. The slot 15' at its lower end, engages the pivot 16' with a running fit, the other end or pivot 16 being held in the slot 15 by means of a clip 18 having an aperture 18' for the pivot which

registers with the slot 15, but as the clip which is adapted to engage the vertical edges of the ear and slide up and down, moves downward, the aperture 18' passes out of registration with the slot.

The weight of the roll is sufficient to move the clip downward and lock the flat pivot with something resembling a wedge action, the weight of the roll acting against the inclined slot 15 to press the edge of the clip on one side and the edge of the ear 14 on the other side, against the flat pivot 16 and lock it in fixed position in the ear 14.

The slides or followers 4, carrying the ends of the stick are quite similar to the followers 9 of the carriages 2 which carry the roll, the slides 4 being provided with ears 20 which are pierced at 21, see Figs. 3 and 4, to engage an eye 22 on the ends of pins 23 thus forming a universal joint between the pins and follower 4. The pins 23 have a sliding engagement with the sticks 24, the pins being seated in a housing 25 which extends lengthwise of the stick. The pulley brackets 26 as illustrated, see Figs. 11, 12 and 13, consist of a wall plate 27 having a horizontal ear 28 to which a horizontal supporting plate 29 is pivotally connected by means of a bolt 30, the plate 29 having a tongue 31 to engage slots 32 in the wall plate 27. These slots are separated from each other by an arc of 90 degrees concentric with the bolt 30 and serve to hold the supporting plate 29 in various positions of adjustment relatively to the wall plate 27, either parallel thereto extending forward or back, or at right angles to the wall plate. This provides for use of the pulley bracket either on the front face or the inner face of the window casing. The pulleys are mounted to rotate on a pin or axle 33 mounted in depending ears 34, the pin being of sufficient length to support one or two pulleys depending on whether the bracket is to be used on the near or far side of the window casing, near or far being used relative to the vertical pull cord 35, see Fig. 1.

The operation of the device is quite apparent from the drawings. The universal joints carrying the ears 14 make it possible to swing them laterally as well as in a vertical plane, so that the carriages can be used on either the front or inner face of the casing, and the universal joints connecting the pins 23 to the stick followers 4 give an adjustment which renders the use of this feature as convenient in one position as the other.

It will be apparent that the various parts of the device with the exception of the cone 7 of the intermediate supports, may be stamped out of sheet metal and bent to their present form with comparatively little expense and that the entire device, owing par-

ticularly to the flexible guide rods, may be packed in a small space. However, when used with the supports described, the guides are sufficiently rigid to prevent flapping.

5 I have thus described specifically and in detail a single embodiment of my invention in order that the nature of the device and its operation may be clearly understood by those skilled in the art, however, the specific 10 terms herein are used descriptively rather than in their limiting sense and the scope of the invention is defined in the claims.

I claim:

1. A window shade fixture consisting of a 15 roll, carriages therefor, flexible guide rods on which the carriages travel, means for moving the roll and carriages up and down the guide rods and means for supporting the guide rods at short intervals throughout 20 their length, the guide rods being so flexible that they may be rolled or folded, the whole device being thus packed in a small space for shipment.

2. A window shade fixture consisting of a 25 roll, a carriage therefor, flat flexible guide rods on which the carriages travel, means for moving the roll and carriages up and down the guide rods and means for supporting the guide rods at short intervals 30 throughout their length, the guide rods being so flexible that they may be rolled or folded, the whole device being thus packed in a small space for shipment.

3. In a window shade construction, a roll, 35 flat guide rods, followers engaging the rods, ears for the followers, universal joints connecting the ears to the followers, the ears being slotted and the roll provided with pivots to engage the slots, and means for 40 moving the followers and roll up and down the length of the window, the followers moving over the guide rods.

4. In a window shade construction, a roll, 45 flat guide rods, followers engaging the rods, ears for the followers, the ears being pivotally connected to the followers to swing horizontally relatively thereto and apertured to receive the roll pivots, and means for moving the followers and roll up and down

the length of the window, the followers 50 moving over the guide rods.

5. In a window shade construction, a roll, 55 vertical guide rods in the form of flat straps, followers engaging the straps, ears for the followers, universal joints connecting the ears to the followers, the ears being slotted and the roll provided with pivots to engage the slots, and means for moving the followers and roll up and down the length of the window, the followers moving over the guide rods.

6. In a window shade construction, a roll, 65 vertical guide rods in the form of flat straps, followers engaging the straps, ears mounted on the followers, the ears being pivotally connected to the followers to swing horizontally relatively thereto and apertured to receive the roll pivots, and means for moving the followers and roll up and down the length of the window, the followers moving 70 over the guide rods.

7. In a window shade construction, a roll, 75 vertical guide rods in the form of flexible flat straps, followers engaging the straps, ears for the followers, universal joints connecting the ears to the followers, the ears being slotted and the roll provided with pivots to engage the slots, means for moving the followers and roll up and down the length of the window, the followers moving 80 over the guide rods, and intermediate supports for the guide rods placed at short intervals throughout the length of the rods.

8. In a window shade construction, a curtain roll and stick, vertical guide rods, four 85 followers engaging the rods, means carrying the roll pivotally connected to the upper followers to swing horizontally relatively thereto and means carrying the curtain stick likewise connected to the bottom followers 90 and means for moving the roll up and down the guides.

Signed by me at Baltimore, Md., this 20th day of July, 1914.

FREDERICK H. KNAPP.
